US00D985554S

(12) **United States Design Patent** (10) Patent No.: **US D985,554 S**
(45) Date of Patent: ** May 9, 2023

(54) **WEARABLE DEVICE**

(71) Applicant: **Google LLC**, Mountain View, CA (US)

(72) Inventors: **Junyong Park**, San Francisco, CA (US); **Benjamin Patrick Robert Jean Riot**, Alamo, CA (US); **Irina Igorevna Kozlovskaya**, San Francisco, CA (US); **Eric John Fairbanks**, Lafayette, CA (US); **Brian Dennis Paschke**, San Francisco, CA (US); **Cedric Eric Jean-Edouard Bernard**, San Francisco, CA (US); **Jonah Avram Becker**, San Francisco, CA (US); **Gregoire Ludovic Vincent Vandenbussche**, San Francisco, CA (US)

(73) Assignee: **GOOGLE LLC**, Mountain View, CA (US)

(**) Term: **15 Years**

(21) Appl. No.: **29/797,847**

(22) Filed: **Jul. 2, 2021**

(51) LOC (14) Cl. **10-02**
